US00D743816S

(12) **United States Design Patent**
Schroedter

(10) **Patent No.:** **US D743,816 S**
(45) **Date of Patent:** **** Nov. 24, 2015**

(54) **MEASURING AND DISPENSING APPARATUS**

(71) Applicant: **Easy Go Dispenser, LLC**, Chicago, IL (US)

(72) Inventor: **Blake Schroedter**, Chicago, IL (US)

(73) Assignee: **Easy Go Dispenser, LLC**, Chicago, IL (US)

(**) Term: **14 Years**

(21) Appl. No.: **29/439,387**

(22) Filed: **Dec. 11, 2012**

Related U.S. Application Data

(63) Continuation-in-part of application No. 13/091,818, filed on Apr. 21, 2011, now Pat. No. 8,439,231.

Schroedter: "Measuring and Dispensing Apparatus"; U.S. Appl. No. 13/091,818, filed Apr. 21, 2011.

Primary Examiner — Ian Simmons

Assistant Examiner — Shannon Morgan

(74) *Attorney, Agent, or Firm* — Keating & Bennett, LLP

(57) **CLAIM**

The ornamental design for a measuring and dispensing apparatus, as shown and described.

DESCRIPTION

FIG. 1 is a top, front side perspective view of a measuring and dispensing apparatus showing my new design;

FIG. 2 is another top, front side perspective view thereof;

FIG. 3 is a bottom, front side perspective view thereof;

FIG. 4 is another bottom, front side perspective view thereof;

FIG. 5 is a bottom, rear side perspective view thereof;

FIG. 6 is a top, rear side perspective view thereof;

FIG. 7 is a front side elevational view thereof;

FIG. 8 is a rear side elevational view thereof;

FIG. 9 is a left side elevational view thereof;

FIG. 10 is a right side elevational view thereof;

FIG. 11 is a top plan view thereof; and,

FIG. 12 is a bottom plan view thereof.

The broken lines shown in FIGS. 1-12 represent portions of the measuring and dispensing apparatus that form no part of the claimed design.

1 Claim, 12 Drawing Sheets
